UNITED STATES PATENT OFFICE

WILLARD F. RICHARDS, OF DEPEW, NEW YORK, ASSIGNOR TO GOULD COUPLER COMPANY, OF NEW YORK, N. Y.

CAR-COUPLING.

1,136,554.

Specification of Letters Patent.

Patented Apr. 20, 1915.

Application filed January 14, 1914. Serial No. 812,124.

To all whom it may concern:

Be it known that I, WILLARD F. RICHARDS, a citizen of the United States, residing at Depew, in the county of Erie and State of New York, have invented a new and useful Improvement in Car-Couplers, of which the following is a specification.

This invention relates to railway car couplers of that kind in which the coupler head is pivoted to the shank or draw-bar and is normally retained in a central position by a centering device which allows the head to swing sidewise in either direction when the cars carrying the couplers are rounding curves.

The objects of the invention are to provide a centering device of simple and practical construction by which the coupler head is normally retained in its central relation to the shank and returned to such position when permitted to after being swung to either side; also to make the coupler head easily removable from the shank and arrange the centering device so that it is removed from the shank with the coupler head and is thus readily accessible; and also to make the construction such that the centering device operates on the head with the maximum leverage, thus enabling the use of an operating spring of minimum size.

In the accompanying drawings: Figure 1 is a fragmentary plan view, partly in horizontal section, of a car coupler and shank embodying the invention. Fig. 2 is a side elevation partly in vertical section thereof. Fig. 3 is a transverse section through the shank in line 3—3, Fig. 2. Fig. 4 is a view similar to Fig. 1, showing the coupler head swung to one side.

40 A represents the head of a car coupler and B the shank thereof. These parts, except as hereinafter explained, may be of any suitable construction. The shank preferably consists of a hollow steel casting.

45 The coupler head is provided with a neck C projecting rearwardly therefrom, preferably into the open front end of the shank B, and is pivotally connected to the shank by a vertical pin or bolt D which passes through 50 registering holes in the shank and neck C and permits the head to swing laterally to either side from a central position relative to the shank. A pivotal connection of any suitable construction could be employed, but 55 preferably a headless pivot bolt D is em-

ployed which is adapted to be inserted into and removed from the holes in the shank and neck C from below the coupler shank. The bolt D is supported in place by a removable key or gib E inserted through a transverse key-slot e in the upper end of the bolt above the top of the shank. The key E shown is provided in its top edge between its ends with a notch e' wide enough for the upper edge of the key-slot e to seat therein between the raised end portions of the key, and the key-slot e in the bolt is deep enough for the passage of the deep end portions of the key. The key is also preferably adapted to rest in a shallow seat or slot g in the top of the shank B which assists in preventing the disengagement of the key from the bolt and prevents the bolt from turning. To secure the bolt it is pushed upwardly through the holes in the shank and neck until the key-slot is fully exposed above the top of the shank B and the key E is inserted into the slot e in the bolt and the bolt allowed to drop until the top edge of the key-slot e is seated in the notch e' in the key and the key rests in the seat g. The key cannot then be removed without first lifting the bolt to raise the upper edge of the key-slot e out of the notch e' and lift the key out of the seat g. A nut H, or other suitable device, is applied to the lower end of the bolt to prevent the latter from lifting and permitting the accidental disengagement of the key. A nut screwed on a thread at the lower end of the bolt is preferred since by tightening the nut the bolt can be drawn downwardly to firmly seat and hold the key E and to tighten the pivotal connection between the coupler head and the shank.

h indicates a cotter pin for preventing the nut from loosening.

To remove the bolt D for detaching the head from the shank the nut H is first unscrewed enough for the bolt to be lifted until the key E can be withdrawn from its slot e, after which the bolt is pulled out downwardly and the coupler head is pulled forwardly off of the shank. This bolt construction makes it possible to detach a coupler head from a shank which is in place on a car without disturbing the shank or the draft rigging, since the detachment is effected from below.

The centering device for yieldingly retaining the coupler head in its central posi-

tion and returning it to such position from its deflected position at either side, is preferably constructed as follows: The neck C of the coupler head projects into the hollow shank for a considerable distance beyond the pivot bolt D and is preferably tapered or provided with rearward converging sides to permit a greater deflection of the coupler head. At the rear or inner end of the neck 5 shank is slidably mounted a shoe or device I which is pressed by a spring K against a V-shaped or double inclined transverse surface l l' in the shank B. As shown, this V-shaped surface is formed by an integral V-shaped cross-bar or web L in the shank. When the coupler head is swung to either side of its central position, the device I will be moved 10 forwardly on the neck by contact with one of the inclined faces of the cross-bar L and will compress the spring K, and when the coupler head is released the pressure of the spring will cause the device I to slide down the incline into the angle of the V-bar, thereby returning the coupler head to its central 15 position, in which it will be yieldingly retained by the pressure of the spring tending 20 to hold the device I in the angle of the V-bar.

As shown, the neck is made hollow, having 25 top and bottom walls i connected by upright side webs i' and is provided on the inner sides of its top and bottom walls with longitudinal grooves or guideways i² into which top and bottom ribs on the device I 30 enter to guide the slide in its movements on the neck. The device I is preferably provided at its rear end with an anti-friction roller i³ by which it bears against the inclined surfaces of the V-bar L, the anti-friction 35 roller being suitably journaled in a cavity in the rear end of the device. The spring K is a coil spring arranged in the hollow neck between the slide I and a bearing portion k on the neck adjacent to the pivot bolt. The slide and bearing portion 40 of the neck are preferably provided with studs k' k² which project into the opposite ends of the spring for retaining the same in position. The described construction of the centering device, the spring-actuated slide or device I and the inclines on which it reacts 45 are located at the end of a long neck or arm on the coupler head at a considerable distance from the pivotal connection and therefore operate with a long leverage so that a comparatively small spring furnishes the necessary force to right or center the coupler head. The movable slide or device I 50 and its operating spring are mounted on the neck and are removable therewith from the shank, and there are no working parts mounted in the shank. The working parts of the device can therefore be readily assembled and are readily accessible for repairs 55

by detaching the coupler head from the shank, and there are no inaccessible parts in the shank which require machining or assembling.

M represents upright shoulders on the 70 coupler head at opposite sides of the neck C adapted to engage coöperating shoulders on the shank to limit the deflection of the coupler head.

The inner or rear end of the neck preferably extends between internal transverse ribs n n' on the top and bottom walls of the shank, or into bearing relation to other suitable parts of the shank for the purpose of relieving the pivot bolt from strain due 80 to the weight of the overhanging coupler head or to vertical stresses thereon.

I claim as my invention:

1. In a car coupler, the combination of a coupler head, a shank to which said head is pivotally connected, said head having a neck which extends longitudinally of said shank beyond said pivotal connection, stationary inclines on said shank, and a spring-pressed device movably mounted on said neck and engaging said inclines for centering said head on said shank. 85

2. In a car coupler, the combination of a chambered shank provided interiorly with inclined faces, a coupler head pivoted to 95 said shank and having a neck extending into the shank, a device movably mounted on said neck, and a spring which presses said device against said inclined faces for centering the head on the shank. 100

3. In a car coupler, the combination of a chambered shank provided interiorly with a stationary V-shaped transverse surface, a coupler head pivoted to said shank and having a neck extending into the shank beyond the pivot for the head, a device mounted to slide longitudinally on said neck, and a spring which presses said device against 105 said V-shaped surface.

4. In a car coupler, the combination of a chambered shank, a coupler head having a neck pivoted to said shank and extending into the shank beyond said pivot, a spring-pressed device which is movable on the rear end portion of said neck, and inclines in 110 said shank against which said device reacts to center the coupler head on the shank. 115

5. In a car coupler, the combination of a chambered shank, a coupler head having a neck pivoted to said shank and extending into the shank beyond said pivot, a device mounted to slide on said neck longitudinally of the shank, a spring which is arranged between said device and a portion of said neck and presses said device rearwardly, and inclines in said shank against which said device reacts to center the coupler head on the shank. 120

6. In a car coupler, the combination of a chambered shank, a coupler head having 125

a chambered neck pivoted to said shank and extending into the shank beyond said pivot, a device arranged to slide in said neck, a coil spring in said neck which acts on said device, and inclines in said shank against which said device reacts to center the coupler head on the shank.

7. In a car coupler, the combination of a chambered shank, a coupler head removably pivoted to said shank and having a neck extending longitudinally of the shank, and a device which is mounted on said neck and acts lengthwise of the neck against said shank for centering the coupler head relative to the shank, said device being removable with said head from said shank.

8. In a car coupler, the combination of

a chambered shank, a coupler head pivoted to said shank and having a neck extending into the shank beyond the pivot for the 20 head, means carried by said neck and acting lengthwise thereof for centering the coupler head relative to the shank, and parts on the shank against which the inner portion of said neck is adapted to bear to relieve the said pivot from strain due to the 25 weight of the coupler head or vertical stresses thereon.

Witness my hand, this 6th day of January, 1914.

WILLARD F. RICHARDS.
